Cornelius L. Ebert

Associate ATTORNEY.

UNITED STATES PATENT OFFICE

JOHN M. MILLER, OF PHILADELPHIA, PENNSYLVANIA, ASSIGNOR TO ATWATER KENT MANUFACTURING COMPANY, OF PHILADELPHIA, PENNSYLVANIA, A CORPORATION OF PENNSYLVANIA

SYSTEM FOR REDUCING OR ELIMINATING REACTION

Application filed November 1, 1926. Serial No. 145,539.

(GRANTED UNDER THE ACT OF MARCH 3, 1883, AS AMENDED APRIL 30, 1928; 370 O. G. 757)

My invention relates to the reduction or elimination of reaction of one circuit or path upon another, due to disturbing alternating or fluctuating potential in one of them, and particularly as regards high or radio frequency currents as utilized in systems of radio communication or in high frequency carrier wave systems utilizing conductors between stations.

- 10 In accordance with my invention, the reaction upon the input circuit of a three electrode thermionic device by a disturbing electro-motive-force in a remote circuit, such as a circuit immediately or remotely coupled to the output circuit of said device, is materially reduced or eliminated, as for the prevention of self-oscillation, by connecting capacities or capacitative reactances between the remote circuit or path and the cathode 20 of the thermionic device to define a point between them at which the potential variations caused by the reaction are in phase with the disturbing electro-motive-force and at which the potential differs substantially from that of the cathode of the thermionic device, and connecting the terminals of an input element to the point so defined and to the grid of the thermionic device, respectively.
- 30 Further in accordance with my invention, there may be simultaneously utilized with the arrangement above described a connection from the point defined as aforesaid through a reactance, such as a capacity, to a point, such as the anode, in the output circuit of the thermionic device.

- 40 In the arrangement first above described, there is formed in effect a Wheatstone bridge in two of whose arms are capacities consisting of or including capacities between grid and remote circuit or path and between grid and cathode, and in the remaining arms of which are included capacities connected between the remote circuit and the aforesaid point and between the aforesaid point and cathode of said device, respectively; and in the second arrangement above described, a portion of the aforesaid bridge is common to a second 50 Wheatstone bridge.

My invention resides in a system of the character hereinafter described and claimed.

For an understanding of my invention, and for an illustration of one of the various forms it may take, reference may be had to the accompanying drawings, in which:

Fig. 1 is a diagrammatic view of a circuit arrangement in accordance with my invention.

Fig. 2 is a diagram of a compound Wheatstone bridge circuit corresponding in general with the circuit arrangement of Fig. 1.

Referring to Fig. 1, D represents a receiving antenna or equivalent absorption structure of a radio receiving system, or, generically, any conductor, including a conductor extending between stations in a high frequency carrier wave system, traversed by the received energy.

In the example illustrated, between the antenna and earth or counter-capacity E is connected the primary L of a radio frequency transformer to which is coupled the secondary S shunted by the variable tuning condenser K, the secondary S and condenser K 70 constituting an input element one of whose terminals is connected to the grid G of the thermionic device or vacuum tube V, as of the audion type, and serving in the example illustrated as a radio frequency amplifier. The other terminal of the input element is connected to the point O between which and a terminal of the cathode or filament F is connected a capacitative reactance C4. Between the grid G and the filament F may be connected a high resistance R.

For exciting the cathode F there is provided the source of current or battery A, and a second source of current or battery B is included in the anode circuit between the anode or plate P and the cathode F along with the primary of a radio frequency transformer T, whose secondary S1 is shunted by the tuning condenser K1 and constituting the input element of a second stage radio frequency amplifier, or, as indicated, of a detector tube V1, between whose grid g and one terminal of the input element S1, K1 is included the usual grid condenser K2; and between the grid g and the filament or cathode f is connected a high resistance 100

1. In the plate or anode circuit of the tube V1 is included the source B and a signal-translating instrument I, such as a telephone or loud speaker, or means for coupling the output circuit of the tube V1 to some subsequent stage or device. Connected between the plate *p* and the cathode *f* is a low reactance or by-path condenser K3, for providing a short circuit for the radio frequency component of the plate circuit around the instrument I and source B.

Between the input circuit or grid G of the tube V and some remote circuit or path, there may exist a capacity such as indicated in dotted lines at C6. The remote circuit or path may be immediately or remotely coupled or related to the output circuit of the tube V. In the example illustrated, the remote circuit is the input circuit of the tube V1.

The remote circuit or path is coupled, as regards fluctuating, alternating or oscillatory disturbing electro-motive-forces, through the capacity C6 with the input circuit or grid G of the tube V, with consequent reaction thereon tending to instability of the system or to the production of parasitic or undesired oscillations.

To reduce or eliminate such reaction, there is utilized a condenser C5 connected between the point O and the remote circuit or path where the disturbing electro-motive-forces exist.

The point O, because of the reactance of the capacity C4, is at a substantially different alternating, fluctuating or oscillatory potential from that of the cathode F, the magnitude of the reactance occasioned by the capacity C4 being substantial for this purpose and distinguishable from a large, by-passing or stopping condenser.

Between the grid G and the cathode F and plate P are intra-tube capacities which may be designated, respectively, C1 and C2.

As indicated in Fig. 2, the capacities C1, C4, C5 and C6 form in effect a true or Wheatstone bridge, a network which may be substantially perfectly balanced. In one conjugate conductor of the bridge, to wit, that between the grid G and the point O, is connected the input element, as S, K; and in the other conjugate conductor, extending between the cathode F and the point H, is included any suitable portion of the remote circuit or path wherein the disturbing electro-motive-forces exist. In the example illustrated, in the second named conjugate conductor is included the input element, as S1, K1 in the input or grid circuit of the tube V1.

In this bridge there is accordingly utilized an intra-tube capacity, for example, that between the grid G and cathode F, which capacity by itself, or in association with additional capacity, if desired, constitutes or is included in one arm of the bridge.

Between the point O and a suitable point,

as the plate P, in the output circuit of the tube V1, is connected a reactance C3, which, as indicated, is a capacity utilized in the relation described in my prior application Serial No. 653,490, filed July 24, 1923.

As indicated in Fig. 2, the capacity C3, with the capacity C2 between the grid G and plate P, form with the aforesaid capacities C1 and C4 a second true or Wheatstone bridge which may be substantially perfectly balanced. The capacity C2 may constitute solely the capacity between grid and plate, or it may comprise that capacity and additional external capacity.

The bridge comprising the capacities C5 and C6 has the effect of preventing the disturbing electro-motive-forces in the remote circuit or path from substantially influencing the potential of the grid G when the bridge is substantially balanced, thereby effecting stability and preventing production of oscillations.

Similarly, the second bridge including the reactance C3 prevents substantial effect upon the potential of the grid G by disturbing electro-motive-forces in the output circuit of the tube V, again yielding as regards these last-named disturbances stability and prevention of oscillation production. Where the input elements S, K and S1, K1 are tuned or tunable, the reaction of the remote circuit or path upon the input or grid G of the tube V will usually affect the operation of the amplifier V and will cause it to become unstable and to generate self-oscillations for certain relative tuning of these two circuits. The arrangement or bridge system described eliminates or reduces this reaction, preventing self-oscillation and yielding stability. For this purpose the condenser C5 is connected between the point O and a point as H, at which latter may be or will be an alternating or fluctuating potential high relative to or differing substantially from the potential of the circuit adjacent to the batteries A and B.

If each of the two bridges indicated is separately balanced, there will be no reaction upon the input element or grid of the tube V regardless of the phase of the disturbing or reacting electro-motive-forces.

If the phase of the potential of the remote circuit or path or of the point H is the same as or 180 degrees from the phase of the potential of the plate P, a balance of the reaction on the input element or grid of the tube V can be obtained when both bridges are out of balance, the lack of balance in one bridge counteracting the lack of balance in the other.

Generally, it may be desirable to balance the bridges separately with respect to the different disturbing electro-motive-forces.

The invention herein described may be manufactured and used by or for the Gov-

ernment of the United States for governmental purposes without the payment to me of any royalty thereon or therefor.

What I claim is:

5. The method of reducing or eliminating the effect upon the input element associated with the grid and cathode of a thermionic device of a disturbing potential in a remote circuit or path external to but influenced by the anode circuit of said device, which comprises connecting capacitative reactances between the remote circuit or path and the cathode of said thermionic device to define a point between them whose potential varies in phase with the disturbing electro-motive-force and differs substantially from said cathode, and impressing the input energy through said input element between said point and the grid. 10

15. The method of reducing or eliminating the effects upon the input element associated with the grid and cathode of a thermionic device of disturbing potentials in the output circuit of said device and in a remote circuit or path, which comprises connecting capacitative reactances between the remote circuit or path and the cathode of said thermionic device to define a point between them whose potential varies in phase with the disturbing electro-motive-force and differs substantially 20 from said cathode, introducing a capacitative reactance between said point and said output circuit, and impressing the input energy through said input element between said point and the grid. 25

30. The combination with a three electrode thermionic device having input and output circuits, of means for reducing or eliminating the effect exerted through an inherent capacity upon the grid of said thermionic device of a disturbing potential in a circuit remote from said output circuit, comprising a bridge in one arm of which is included said inherent capacity, in another arm of which is included the capacity between grid and cathode of said thermionic device, and the other two arms of which include capacities, an input element connected in the conjugate conductor one of whose terminals is connected to the junction of said two first-named arms, and the other conjugate conductor of said bridge having impressed thereon the disturbing potential. 35

40. The combination with a three electrode thermionic device having input and output circuits, of means for reducing or eliminating the effect of a disturbing potential in a circuit remote from said output circuit comprising a reactance connected between a point in said input circuit and the cathode of said thermionic device, a capacity connected between said point and a point in said remote circuit or path of potential substantially different from cathode potential for alternating currents, and an input element having its terminals connected, respectively, to said first 45

said remote circuit of potential substantially different from cathode potential for alternating currents, and an input element having its terminals connected, respectively, to said point and the grid of said thermionic device, said remote and input circuits being in conjugate conductors of a bridge in different arms of which are disposed said first named reactance and said capacity, other arms of said bridge comprising respectively, capacity between said remote circuit and said input circuit, and impedance between input electrodes of said tube.

8. The combination with a three electrode thermionic device having input and output circuits, and a remote circuit associated with said output circuit, of a bridge having a capacity in each arm thereof, a capacity in one of said arms including the capacity between the grid and cathode of said thermionic device, an input element connected in one conjugate conductor of said bridge, and a portion of said remote circuit included in the other conjugate conductor of said bridge.

25 9. The combination with a three electrode thermionic device having input and output circuits, and a remote circuit associated with said output circuit, of a bridge having a capacity in each arm thereof, a capacity in one of said arms including the capacity between the grid and cathode of said thermionic device, a second bridge having two arms in common with said first named bridge, a third arm of said second bridge including capacity comprising the capacity between plate and grid of said thermionic device, said bridges having a common conjugate conductor, an input element connected in said common conjugate conductor, and a portion of said remote circuit included in the other conjugate conductor of said first named bridge.

40 10. The combination with a three electrode thermionic device having input and output circuits, and a remote circuit influenced by said output circuit, of a bridge having a capacity in each arm thereof, a capacity in one of said arms including the capacity between the grid and cathode of said thermionic device, an input element connected in one conjugate conductor of said bridge, a portion of said remote circuit included in the other conjugate conductor of said bridge, a second bridge including two of the capacities of said first named bridge, said first named conjugate conductor of said first named bridge constituting a conjugate conductor of said second bridge, a winding in the other conjugate conductor of said second bridge, and a winding in said remote circuit coupled to said 55 winding.

60 11. The combination with a three electrode thermionic device having input and output circuits, of a bridge having a capacity in each arm thereof, one of said capacities including the capacity between electrodes of said ther-

mionic device, an input element connected in one conjugate conductor of said bridge, a second thermionic device, and an input circuit therefor comprised in the second conjugate conductor of said bridge.

12. The combination with a three electrode thermionic device having input and output circuits, and a remote circuit associated with said output circuit, of capacities connected in series with each other between the anode and cathode of said thermionic device and forming a bridge with capacities including the grid-anode and grid-cathode capacities of said thermionic device, an input element connected in a conjugate conductor of said bridge, and a capacity in a connection from a point between said first named capacities and a point in said remote circuit of potential substantially different from cathode potential for alternating currents.
